UNITED STATES PATENT OFFICE.

WILLIAM T. DORGAN, OF SAGINAW, MICHIGAN.

DESIGN FOR A TIRE-TREAD.

41,994.

Specification for Design.

Patented Dec. 19, 1911.

Application filed April 10, 1911. Serial No. 620,233. Term of patent 14 years.

To all whom it may concern:

Be it known that I, WILLIAM T. DORGAN, a citizen of the United States, residing at Saginaw, in the county of Saginaw and State of Michigan, have invented a new, original, and ornamental Design for Tire-Treads, of which the following is a specification, reference being had to the accompanying drawing, forming part thereof.

The figure is a plan view of part of a tire tread, showing my new design.

I claim:

The ornamental design for a tire tread, as shown.

WILLIAM T. DORGAN.

Witnesses:

CHRISTINE A. BRAIDEL,
GEO. W. SMITH.
